VALVE MECHANISM FOR FLUID PRESSURE
TOOLSEdward W. Stevens, Detroit, Mich., assignor to
Chicago Pneumatic Tool Company, New York,
N. Y., a corporation of New JerseyApplication December 27, 1929
Serial No. 416,783

2 Claims. (Cl. 121—19)

This invention relates to fluid pressure tools and more particularly to improvements in the valve mechanism for the same.

One object of the invention is to provide very simple and compact valve mechanism which will permit the construction of compact tools having rapid powerful action with low air consumption. Another object is to minimize the effect of wear on the valve parts and to reduce repair and replacement expense to a negligible amount. Another object is to provide a small light valve with a very short throw which valve can be cheaply made of any suitable or desired material and has only one surface requiring accurate machining. Other objects will be apparent from the detailed description which follows.

In order to illustrate the invention one concrete embodiment thereof is shown in the accompanying drawing in which:

Fig. 1 is a side elevational view largely in section through a pneumatic tool;

Fig. 2 is a fragmentary view showing the sectioned portions of the tool of Fig. 1 with the piston and valve in different positions the section being substantially on the line 2—2 of Fig. 3; and

Fig. 3 is a transverse sectional view substantially on the line 3—3 of Fig. 2.

While the invention is capable of general application to all fluid pressure tools in which a valve controls the reciprocations of another member, the embodiment chosen for the purpose of illustration comprises a small hand tool of the type usually referred to as a chipping hammer. This tool has a cylinder 4 providing a piston chamber 4a within which reciprocates piston 5 to strike blows upon the shank of a working tool 6 inserted into the front end of the cylinder. The rear end of the cylinder is closed by the usual throttle handle 7 having an extension 7a in threaded engagement with the exterior of the cylinder and providing an inlet passage 8 for motor fluid.

In the tool shown the valve mechanism for controlling the movement of piston 5 is disposed within handle extension 7a and clamped against the end of cylinder 4 providing a valve chamber 9a in line with piston chamber 4a. The valve chamber is formed by the bore of a ring-shaped valve case 9, which bore is substantially circular but is elongated slightly in a direction transverse to the axis of the cylinder (Fig. 3). Clamped between case 9 and cylinder 4 is a closure member or lid 10 forming a partition between the valve chamber and the piston chamber. While

the closure for the other end of the valve chamber may be integral with case 9 or may be provided by handle 7, in the present instance it is a separate member or plate 11. Dowels 9b (Fig. 3) maintain case 9 and lid 10 in proper relation with cylinder 4. Mounted in the valve chamber 9a with its opposite edges in free sliding engagement with closures 10 and 11 is a simple tubular valve 12 in the form of a narrow imperforate ring.

All of the ports entering the valve chamber to affect or to be affected by the position of valve 12 are disposed in case 9 in the same transverse plane. Motive fluid is admitted to the valve chamber by an annular series of spaced ports 13, 14, 15 and 16, which constantly subject the exterior of valve 12 to live motive fluid. These ports comprise opposed pairs 13, 15 and 14, 16. The short live air passages extending to ports 13 and 14 on one side of the median line of the valve chamber are much smaller than those leading to ports 15 and 16 on the other side so that when the valve is in the position shown in Figs. 2 and 3 a much greater quantity of motive fluid is admitted to the piston chamber than when in the position shown in Fig. 1. Between inlet ports 13 and 14 is outlet port 17 from which extends a passage 18 through cap 10 and axially through the wall of cylinder 4 to open into the forward end of the piston chamber by a port 18a for motive fluid to drive the piston on its rearward or non-working stroke. Directly opposite outlet port 17 in valve case 9 is another outlet port 19 intermediate inlets 15 and 16 which communicates with a short passage 20 through cap 10 and opening directly into the rear end of the piston chamber for motive fluid to drive the piston on its forward or working stroke. Since all of the ports in valve case 9 opening into the valve chamber 9a are annularly disposed in the same plane, the movement of motive fluid from the inlet to the outlet is most free and direct. Valve 12 controls only the admission of motive fluid to piston chamber 4a. The exhaust of motive fluid is controlled by piston 5 as it overruns ports 21a and 21b which open into an axial passage 21 in cylinder 4 with vents directly to atmosphere.

The throw of the valve is effected by a combination of line and built-up pressure on the one side and a reduced pressure on the other. For example, in Fig. 1 the valve has just shifted to the lower side to seal outlet port 19 communicating with the rear piston chamber now at reduced or atmospheric pressure by the un-

covering of vent port 21b by piston 5, and to admit motive fluid in the restricted quantity determined by the size of the live air passages to inlet ports 13 and 14 through passage 18 for driving piston 5 on its rearward stroke. When piston 5 uncovers vent port 21a and seals vent port 21b pressure is reduced in outlet port 17 of the valve case and built up in outlet port 19 by the air trapped and compressed by the piston 10 as it moves rearwardly. In consequence, the valve shifts to the position shown in Figs. 2 and 3 whereupon live motive fluid in full volume determined by the large live air passages leading to inlet ports 15 and 16 is immediately available in the rear end of the piston chamber to reverse piston 5 for a powerful working stroke. Just before the blow is struck the piston opens vent port 21b and seals port 21a with the result that pressure falls in outlet port 19 but is built 20 up in outlet port 17, thus causing the valve to shift again and complete the cycle.

I am aware of previously known forms of long tubular valves such as disclosed in German Patents Nos. 217,428 and 218,081, also in British 25 Patents 192,277, 208,961 and 210,662, but my invention is a distinct advance over these in that the parts are much simplified resulting in a much lighter and more compact tool. Still more important is the improved operation, the 30 faster and more powerful blows, and the decreased air consumption. Without doubt the small size and light weight of the valve, its short throw, and the novel arrangement of portings in the valve case with the balancing of pressures 35 on the valve are contributing factors in securing the many advantages of this invention.

While the invention has been herein disclosed in what is now considered to be a preferred form, it is to be understood that it is not limited to the specific details thereof, but covers all 40 changes, modifications and adaptations within the scope of the appended claims.

I claim as my invention:

1. A fluid pressure tool having a cylinder providing a piston chamber, a piston reciprocable therein, valve mechanism for automatically controlling the distribution of motive fluid to the opposite ends of said chamber comprising a thin cylindrical valve case providing a valve chamber 50

in line with said piston chamber, a partition member interposed between said case and said cylinder, means including a port in said partition member providing a short and direct passage from said case to the rear end of said piston chamber, a closure for the end of said case opposite said partition member, a narrow imperforate ring valve in said valve chamber with its edges slidably engaging said partition member and said closure, means providing a reservoir of motive fluid extending completely around the periphery of said valve case, said valve case having pairs of radial inlet ports extending through opposed portions thereof and radial outlet ports between the inlet ports making up each of said pairs, all of said valve case ports being in the same transverse plane and under control of said valve, one of said outlet ports connecting with said partition port.

2. A fluid pressure tool having a cylinder providing a piston chamber, a piston reciprocable therein, valve mechanism for automatically controlling the distribution of motive fluid to the opposite ends of said chamber comprising a thin cylindrical valve case providing a valve chamber 100 in line with said piston chamber, a partition member interposed between said case and said cylinder, means including a port in said partition member providing a short and direct passage from said case to the rear end of said piston chamber, a closure for the end of said case opposite said partition member, a narrow imperforate ring valve in said valve chamber with its edges slidably engaging said partition member and said closure, said closure being secured to 110 said cylinder for maintaining said valve mechanism parts in assembled relation and providing a motive fluid chamber extending completely around the exterior of said valve case, said valve casing having pairs of radial inlet ports extending through opposed portions thereof and radial outlet ports between the inlet ports making up each of said pairs, all of said valve case ports being in the same transverse plane and under control of said valve, one of said outlet ports connecting with said partition port, and means 115 connecting the other of said outlet ports to the opposite end of said piston chamber.
